US0D1033052S

(12) **United States Design Patent** (10) **Patent No.:** **US D1,033,052 S**
(45) **Date of Patent:** **** Jul. 2, 2024**

(54) **CASE FOR EARPHONE**

(71) Applicant: **GUANGDONG OPPO MOBILE TELECOMMUNICATIONS CORP., LTD.**, Guangdong (CN)

(72) Inventor: **Honglin Liu**, Guangdong (CN)

(73) Assignee: **GUANGDONG OPPO MOBILE TELECOMMUNICATIONS CORP., LTD.**, Guangdong (CN)

(**) Term: **15 Years**

(21) Appl. No.: **29/833,685**

(22) Filed: **Apr. 6, 2022**

(30) **Foreign Application Priority Data**

Oct. 29, 2021 (CN) 202130712536.7

(51) **LOC (14) Cl.** **03-01**

(52) **U.S. Cl.**

USPC **D3/294**; D13/108

(58) **Field of Classification Search**

USPC D3/20, 200, 201, 203.1, 203.2, 203.3, D3/203.5, 203.6, 203.7, 203.8, 204-207, D3/215, 218-221, 225-228, 230, 247, D3/269, 272, 273, 276, 280-284, 289, D3/294, 295, 298-303, 901, 903-905; D6/328, 512, 513, 552, 566, 567, 573, D6/702; D7/600.1, 601, 602, 609, 635, D7/637, 638; D9/414, 420-423, 434, D9/435, 499, 700, 701, 761; D12/415, D12/423-426; D13/108, 152, 184; D14/203.4, 203.5, 203.6, 205, 209.1, 223, D14/229, 251, 252, 509-511; D18/3.2; D24/224-227, 229, 223; D27/172, 186; D99/28; D10/46, 81

(57) **CLAIM**

The ornamental design for a case for earphone, as shown and described.

DESCRIPTION

FIG. 1 is a front, right perspective view of a case for earphone showing my new design;

FIG. 2 is a front, top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the FIG. 4 illustrate portions of the case for earphone that form no part of the claimed design.

1 Claim, 5 Drawing Sheets
